UNITED STATES PATENT OFFICE.

LUTHER P. MILBURN, OF BOULDER, COLORADO.

FURNITURE-POLISH.

1,222,441.

Specification of Letters Patent. Patented Apr. 10, 1917.

No Drawing.

Application filed June 15, 1916. Serial No. 103,720.

To all whom it may concern:

Be it known that I, LUTHER P. MILBURN, a citizen of the United States, residing at Boulder, in the county of Boulder and State of Colorado, have invented or discovered a new and useful Furniture-Polish, of which the following is a description.

My invention pertains to a furniture polish to be used for the purpose of cleaning, 10 polishing and renewing the finish of all finished woods, both varnish and wax-finishes. This polish may also be used advantageously for cleaning marbles, and enamel bath tubs and similar surfaces.

15 My improved composition comprises the following ingredients in substantially the proportions stated, viz: linseed oil, about 25 parts; apple vinegar, about 70 parts; acetic acid one to four parts; and a pungent 20 vegetable oil, preferably oil of peppermint or oil of citronella, about 1 part.

The ingredients named are to be thoroughly mingled by agitation and the polish is then ready for use.

The polish is then applied with any soft 25 cotton cloth or cheese cloth, and it is not necessary that the surface be cleaned before polishing as this composition cleans as well as polishes. To give the desired finish soft cheese cloth should be used on the surface to 30 which the polish has already been applied and should be rubbed lightly.

Having thus described my invention or discovery what I claim and desire to secure by Letters Patent, is:

The herein described composition of matter for a furniture polish, consisting of linseed oil, vinegar, acetic acid, and a pungent vegetable oil, in substantially the proportions stated.

40 In testimony whereof, I have hereunto set my hand in the presence of two subscribing witnesses.

L. P. MILBURN.

Witnesses:

GEORGE POMEROY,
J. TAYLOR SMITH.
